P. M. RAINY AND A. D. DOWD,
TELEGRAPH SYSTEM,
APPLICATION FILED JUNE 22, 1917.

1,378,978.

Patented May 24, 1921.

UNITED STATES PATENT OFFICE.

PAUL M. RAINY, OF GLEN RIDGE, AND ANDREW D. DOWD, OF HOBOKEN, NEW JERSEY, ASSIGNEES TO WESTERN ELECTRIC COMPANY, INCORPORATED, OF NEW YORK, N. Y., A CORPORATION OF NEW YORK.

TELEGRAPH SYSTEM.

1,373,978.

Specification of Letters Patent. Patented May 24, 1921.

Application filed June 22, 1917. Serial No. 176,390.

To all whom it may concern:

Be it known that we, PAUL M. RAINY and ANDREW D. DOWD, citizens of the United States, residing at Glen Ridge, in the county of Essex and State of New Jersey, and at Hoboken, in the county of Hudson and State of New Jersey, respectively, have invented certain new and useful improvements in Telegraph Systems, of which the following is a full, clear, concise, and exact description.

This invention relates to telegraph systems, and more particularly to printing telegraph systems adapted for either manual or automatic transmission.

The principal object of this invention is the provision of means whereby groups of selecting current impulses may be formed and stored ready for transmission while the preceding group of selecting current impulses are being sent to line, thereby making it possible to set up combinations of impulses in rapid succession without loss or mutilation of any impulse.

A further object is the provision of means whereby a plurality of current distributors, located at widely separated stations, may be caused to maintain the proper phase relation without employing complicated and expensive apparatus.

For the accomplishment of the above objects, the invention contemplates the employment of current-control means coöperating with a distributor to form current impulses for the line. The current-control means may comprise an automatic transmitter, or a direct keyboard transmitter including selecting magnets and control magnets, either of which may coöperate with a rotary sending distributor to form characteristic groups of line impulses. The circuit connections of the keyboard transmitter are so arranged that two or more keys may be depressed in rapid succession to form groups of selecting impulses for the line without mutilation or loss of any impulse, thereby providing what is called "a free keyboard." Switching means are also provided whereby either of the current control means may be associated with the distributor. A receiving distributor is also provided which operates in isochronism with the sending

distributor and coöperates with selecting mechanism to distribute the effects of current impulses received over the line. The latter distributor may be utilized, when the line is not working duplex, to distribute the effects of the outgoing line current impulses to a home recording mechanism thereby providing a home copy.

The above and other objects of this invention will be fully set forth in the following description and claims and will be more readily understood by reference to the accompanying drawing in which is disclosed one specific embodiment of the invention.

The system of this invention is here shown adapted for use with a five-unit impulse code using two additional impulses, one a starting impulse which precedes the first signaling impulse and the other a restoring impulse which follows the fifth signaling impulse. Obviously, other codes, such, for example, as the Baudot code consisting of five positive and negative impulses, may be used without departing from the spirit of the invention. The system preferably requires but a single line conductor with a ground return. The apparatus shown in the accompanying drawing is that employed at a single station. It is readily apparent, however, that any number of stations similarly equipped may be interconnected and one station may be sending and all others receiving or any two stations may send and receive simultaneously by providing the usual duplex balance, or two line conductors may be provided, one for receiving and one for sending. A system of this kind finds a ready field in press or news distribution work.

In the accompanying drawing, A and B are two distributor faces parallel to each other, each face consisting of two segmented rings. The distributor brush arms 10 and 110 are frictionally mounted on a constantly rotating shaft 11 which may be driven by any suitable means, for example, a motor. Each arm carries a brush which is adapted to sweep over its respective distributor face and interconnect the segments of the two rings when the brush arm is released as will be hereinafter explained.

The distributor A coöperates with current control means to form current impulses for the line and the distributor B coöperates with selecting mechanism to distribute the effects of current impulses from the line, to operate a receiving or home recording mechanism, for example, a printer.

At 40 is represented a keyboard which may be used for selectively actuating a plurality of current controlling contacts. This mechanism may be of any suitable type but preferably of the type disclosed in Patent No. 1,214,515, dated February 6, 1917.

At the lower left-hand corner of the drawing is shown an automatic current controller 20, controlled by a perforated tape, or the like, which controller may be of any suitable type, as, for example, that disclosed in French Patent 361,261.

A multiple switch 60 is provided for changing from direct keyboard to tape transmission and vice versa. The switch as shown in the drawing is in position for keyboard transmission.

A better understanding of the system can be obtained from a description of the selection of a particular character and the various operations which take place in transmitting and recording the necessary impulses for representing a given character.

Let us assume, for example, that the letter "D" is to be transmitted by the keyboard transmitter 40 and that the combination and sequence of units required are current, no current, no current, current, no current. The movable keyboard contacts 101 to 105 inclusive are selectively closed by the keys, while the common keyboard contact 106 is closed whenever any key is depressed. Now, when the D-key of the keyboard (not shown) is depressed, the movable contacts 101 and 104 are moved into engagement with their respective stationary contacts and the common keyboard contact 106 is also closed. The closing of these contacts completes energizing circuits through the corresponding selecting relays 111 and 114 and the overlap magnet 52. The energizing circuits of the selected relays and overlap magnet may be traced from grounded battery 124, through the right-hand windings of relays 111 and 114 and contacts 101 and 104, respectively, in parallel, armature 125 of lock-out magnet 51, armature 126 of keyboard magnet 50, winding of overlap magnet 52, common keyboard contact 106, to ground. Magnet 52 pulls up its armatures 116 and 117 and establishes a holding circuit for itself, from grounded battery 177, armature 117 and front contact thereof, winding of magnet 52, contact 106, to ground. This circuit will be maintained as long as any key of the keyboard is depressed. The pulling up of armature 116 does not affect any apparatus

at this time. When the selecting relays are actuated they become locked up, due to flow of current from grounded battery 124, through the left-hand locking windings of the selected relays, left-hand armatures and contacts thereof, through the winding of the keyboard magnet 50, back contact and armature 178 of lock-out magnet 51, to ground. In addition to locking up the selected selecting relays, current in this circuit also effects the energization of the keyboard magnet 50 which attracts its armatures 126 and 127. The attraction of armature 126 opens the energizing circuit of the selecting relays, but does not affect magnet 52 which is locked up over an independent circuit. The attraction of armature 127 establishes an energizing circuit for the sending start relay 14, which circuit may be traced from grounded battery 13, winding of relay 14, armature 127 and contact thereof, movable switch 16 of multiple switch 60 and lower contact thereof, holding pawl 17, brush arm 10, brush 9, segment 21 to ground. Relay 14 in pulling up its armature 32 establishes an energizing circuit for start magnet 18, and in pulling up its armature 22 removes battery from the line, thereby causing the deenergization of line relay 34. It is to be understood that the line L will normally be closed and will include a source of current so that when the line is idle or when message signals are not being transmitted, the line relays at the several stations will be maintained energized and will hold their armatures against their front contacts.

The energization of start magnet 18 causes the release of the distributor brush arm 10, so that the brush arm is permitted to rotate, due to its frictional engagement with the constantly rotating shaft 11, to send to the line characteristic impulses as provided by the transmitter 40.

Now, if it is desired to obtain a home record of the outgoing message this may be accomplished by closing the switch 119 so that the distributor B and selecting mechanism 80 will respond to the actuation of the line relay 34. Assuming the switch 119 is closed, then when the line relay 34 is deenergized due to the operation of relay 14, its armature 35 will engage the back contact thereof and complete an energizing circuit for receiving start relay 114 from grounded battery 115, segment 121, brush 109, brush arm 110, holding pawl 117, winding of relay 114, switch 119, contact and armature 35, to ground. The energization of relay 114 completes two circuits, one a temporary holding circuit for itself, the other an energizing circuit for start magnet 118. The energization of magnet 118 effects the withdrawal of holding pawl 117 and permits the distributor brush arm 110 to rotate due to its frictional engagement with the constantly rotating shaft 11.

The distributor brush arms 10 and 110 have both been released, and since both are frictionally mounted on the same rotating shaft, they will travel at approximately the same speed. The distributing faces of distributors A and B are so adjusted relative to each other that the brush 109 will interconnect segments 171, 172, 173, etc., with segment 131 at the same time the brush 9 interconnects segments 71, 72, 73, etc., respectively, with the segment 31. As the brush 9 passes over the segments of the sending distributor A, the circuit of the line wire is closed in accordance with the particular selection set up by the selecting relays; that is, since relays 111 and 114 have been actuated to provide the necessary impulses for the character "D," the line circuit will be closed while the brush 9 passes over segments 71 and 74, and will be opened while the brush passes over segments 72, 73 and 75. It will thus be seen that the character selections are made simply by opening and closing the line circuit as is done in Morse operation.

As soon as brush 9 passes off of segment 70, the circuit for start magnet 18 is broken, thereby permitting holding pawl 17 to fall back and engage the brush arm 10 when it completes a revolution. It will also be observed that as soon as brush 109 passes off of segment 170, the holding circuit for relay 114 will be broken and consequently armatures 122 and 132 will fall back. When armature 132 falls back start magnet 118 will be deenergized and the holding pawl 117 will fall back in the path of travel of the brush arm 110, thereby permitting the brush arm to make only one revolution until the start magnet 118 is again energized.

The instant brush 9 interconnects segments 71 and 31, a circuit will be completed from grounded battery 108, armature 141 of selecting relay 111, movable switch 29 and lower contact thereof, segment 71, brush 9, segment 31, through the winding of line relay 34, to ground at a distant station. Current in this circuit will cause the energization of relay 34 and may also cause the energization of a corresponding relay at a distant station, or there may be a number of relays located at as many different stations, each responding to the impulses sent out by the distributor A.

As hereinbefore mentioned, while brush 9 travels over segment 71, brush 109 likewise travels over segment 171, and when the line relay 34 is energized a circuit is completed from grounded battery 128, winding of selecting magnet 181, segment 171, brush 109, segment 131, armature 35 and front contact thereof, to ground. Current through this circuit will cause the energization of the selecting magnet 181 of the selecting mechanism 80 and cause the selecting mech-

anism to perform some function incident to recording the character "D" for which characteristic impulses are being sent out by distributor A.

The brush arms 10 and 110 have now swept over segments 71 and 171, respectively. An impulse has been sent to line and the effect of the impulse has caused the actuation of one of the selecting magnets of the selecting mechanism 80 to perform some function, such as moving a notched disk or bar in connection with recording the character which is being transmitted. When the brush 9 passes off of segment 71, the circuit through the line relay 34 will be broken and the armature 35 will fall back against its back contact. Now as brush 9 passes over segments 72 and 73, no current will be sent to line, as the selecting relays 112 and 113 have not been energized to connect battery to the respective segments of the distributor, and consequently the line relay 34 will be unaffected. Likewise, the selecting magnets 182 and 183 of the selecting mechanism 80 will not be energized when the brush 109 sweeps over segments 172 and 173, since the circuits through the respective magnets will be opened at the front contact of armature 35. However, when brush 9 interconnects segments 74 and 31, a circuit will be completed from grounded battery 108, armature 144 of selecting relay 114, movable switch 37 and lower contact thereof, segment 74, brush 9, segment 31, line relay 34, line L to ground at a distant station. This will cause relay 34 to attract its armature 35 and since brush 109 is now passing over segment 174, the selecting magnet 184 will be actuated in the same manner as selecting magnet 181 hereinbefore mentioned and described. The brush 9, in passing over segment 75 will not impress current on the line, since the selecting relay 115 has not been energized to connect battery to that segment; consequently, the line relay 34 will not be actuated and therefore the selecting magnet 185 will not be energized when brush 109 sweeps over segment 175. When brush 109 interconnects segments 121 and 176, current will flow from grounded battery 115, segment 121, brush 109, segment 176 to a recording or printing mechanism to record or print the selected character "D." The printing apparatus may be of any suitable type, such, for example, as that disclosed in Patent 1,128,422, dated February 16, 1915.

After brush 109 passes off of segment 176, it will continue to travel until engaged by the holding pawl 117 and will be held by that pawl until the sending start relay 14 is again energized as hereinbefore described.

When brush 9 engages segment 76, current will flow from grounded battery 77, through the winding of stop relay 26, segment 76, brush 9, segment 21, to ground, 130

thereby causing stop relay 26 to attract its armatures 25 and 78. The attraction of armature 78 completes a circuit from grounded battery 79, armature 78 and front contact 5 thereof, movable switch 81 of multiple switch 60 and lower contact thereof, through the winding of lock-out magnet 51 to ground. The attraction of armature 25 breaks the holding circuit of the sending 10 start relay 14, which relay immediately falls off, closing contact 23 and opening contact 33. The opening of contact 33 prevents the energization of start magnet 18 when the brush 9 interconnects segments 70 and 21 15 and the closing of contact 23 provides battery for the various sending stations along the line L.

The actuation of the lock-out magnet 51 performs two functions, first, the attraction 20 of armature 178 opens the locking circuit of the keyboard magnet and selecting relays and also establishes a locking circuit for magnet 51, provided magnet 52 has not been deenergized; secondly, the attraction of armature 125 prevents the premature operation 25 of the selecting relays which are to be selected for the next character combination.

Should any key lever be held depressed, magnet 52 will continue to be locked up; 30 consequently, the lock-out magnet 51 will be locked up by current from grounded battery 179, armature 116 of magnet 52, locking winding of magnet 51, armature 178 and front contact thereof to ground. Unless this 35 provision were made, the same group of selecting impulses would be impressed upon the line repeatedly so long as a particular key lever is held down.

It will also be observed that if a second 40 key is depressed before the group of impulses set up by the actuation of the first key has been wiped off by the distributor brush, a new selection cannot be set up for the reason that the energizing circuits of 45 the selecting relays are open at armature 126 of keyboard relay 50, but the second selection will not be lost provided the second key is held depressed until the lock-out relay 51 falls off and closes the back contact of armature 125. Relay 26 falls off as 50 soon as brush 9 passes off of segment 76, and causes the deenergization of lock-out relay 51. This arrangement allows the operator considerable freedom in manipulating the keys, and also makes it possible to 55 attain a somewhat higher speed. The operation of the receiving distributor B and the selecting mechanism 80 when used for producing a copy of the outgoing message has 60 been described, but it is to be understood that the functioning of the apparatus has been thus described for the sake of simplicity and that the apparatus may be used to record the effects of impulses received over

the line L from a distant station, and in fact 65 would generally be so used.

So far we have considered the operation and co-operation of the rotary distributors, the selecting mechanism and the direct keyboard current control means. At the left-hand side of the drawing is shown an automatic current controller 20 and a multiple switch 60 for connecting the controller 20 to the distributor segments and disconnecting the controller 40 therefrom. The automatic current controller comprises a plurality of movable contacts 1 to 5 inclusive which may be selectively actuated by means of a perforated tape or the like to engage the bus-bar 7 which is connected to a 70 grounded source of battery 8. When using the current controller 20, the multiple switch 60 must be thrown to bring the movable contacts thereof into engagement with the upper stationary contacts, and the switch 19 must be closed. The closure of switch 19 completes a circuit from grounded battery 13, through the energizing winding of sending start relay 14, switch 19, contact 12, movable switch 16 and upper contact 85 thereof, holding pawl 17, brush arm 10, brush 9, segment 21 to ground. Current through this circuit causes relay 14 to attract its armatures 32 and 22, which control the distributor A and B, respectively, as here- 90 inbefore described.

So far as the functioning of the distributors and selecting mechanism is concerned, tape transmission does not differ from direct keyboard transmission, and therefore the 100 operation of the sending and receiving apparatus will not be further described in connection with the tape transmission except to state that when stop magnet 26 is actuated, due to the brush 9 interconnecting segments 21 and 76, an energizing circuit 105 will be completed for the tape feeding magnet 82, from grounded battery 79, armature 78 and front contact thereof, movable switch 81 and upper contact, winding of magnet 82, to ground. Magnet 82 when thus energized moves the tape forward one step to present a new group of perforations for selectively actuating the movable contacts 1 to 5 inclusive. 115

The receiving segments of the distributor B are shown approximately one-fourth the length of the sending segments of distributor A, and therefore, only a small portion of each impulse may be utilized to operate 120 the selecting mechanism. If the brushes at the receiving stations travel in synchronism with the brush at the sending station, then the small portion of each signal impulse which is utilized will be taken from its 125 center and consequently that portion of the impulse which is utilized will be practically free from mutilation due to inductive inter-

ference. Should the brushes not rotate in synchronism, that portion of each signal which is utilized to operate a selecting magnet will be taken from some part of the 5 signal impulses on either side of its center and it will be seen that considerable variation in speed is permissible before an impulse is dropped.

What is claimed is:

1. In a printing telegraph system wherein the characters are represented by permutations of impulses, a group of circuit controlling contacts, means for selectively actuating said contacts, a main line, a current distributor for connecting said contacts sequentially with said line and tending normally to rotate, and means controlled by said distributor whereby said group of contacts may be actuated in rapid succession without loss or 20 mutilation of impulses.

2. In a printing telegraph system comprising a current distributor tending normally to rotate, a main line, a group of circuit controlling contacts, a group of selecting relays controlled by said contacts and cooperating with the distributor to form current impulses for the line, a magnet controlled by said relays for releasing the distributor, and means controlled by the distributor for preventing loss of impulses when said group of contacts is actuated in rapid succession.

3. In a printing telegraph system comprising a distributor tending normally to rotate, a plurality of keys, a group of contacts selectively actuated by each of said keys, a plurality of selecting relays controlled by said contacts, a keyboard magnet energized upon actuation of any selecting relay to release the said distributor, and means controlled by said distributor to cause the deenergization of said keyboard magnet.

4. In a printing telegraph system comprising a distributor tending normally to rotate, a main line, a plurality of keys, a group of contacts selectively actuated by each of said keys, a plurality of selecting relays controlled by said contacts and arranged to cooperate with said distributor to form current impulses for the line, a keyboard magnet energized upon actuation of any selecting relay to release the said distributor, and a lock-out magnet controlled by said distributor to cause the deenergization of said keyboard magnet.

5. In a printing telegraph system comprising a distributor tending normally to rotate, a main line, a plurality of keyboard circuit controlling contacts, a plurality of selecting relays controlled by said contacts and arranged to cooperate with said distributor to form current impulses for the line, energizing and locking windings for said relays, a keyboard magnet in series with

said locking windings and adapted when energized to open the energizing circuits of the selected relays and release the said distributor, and a lock-out magnet controlled by said distributor for preventing the repetition of groups of impulses.

6. In a printing telegraph system wherein the characters are represented by permutations of impulses, a plurality of current controlling contacts, a main line, a current distributor for connecting said contacts in turn with said line and tending normally to rotate, means independent of said current controlling means for controlling the rotation of said distributor, a relay connected in series with the main line and responsive to all line current impulses, and a home recording mechanism comprising a plurality of operating magnets and a rotary distributor controlled by said relay.

7. In a printing telegraph system, a line circuit, a source of current normally in series therewith, a set of selectable contacts associated with said source of current, means for connecting said contacts to said source, a distributor mechanism associated with said contacts, and a relay controlled by said distributor mechanism for initially opening said line circuit and for releasing said distributor to bring said selectable contacts into series relation with the line.

8. In a printing telegraph system comprising a current distributor, a plurality of keyboard circuit controlling contacts, a plurality of selecting relays controlled by said contacts and arranged to cooperate with said distributor to form current impulses for the line, energizing and locking windings for said selecting relays, an overlap magnet in series with said energizing windings and adapted to be energized when any key is depressed, a lock-out magnet controlled by said distributor, and a holding circuit for said lock-out magnet controlled by said overlap magnet.

9. In a printing telegraph system comprising a distributor, a main line, a plurality of keyboard circuit controlling contacts, a plurality of selecting relays controlled by said contacts and cooperating with said distributor to form characteristic groups of current impulses for the line, and means controlled by said keyboard contacts and said distributor whereby two or more keys may be depressed in rapid succession without loss or mutilation of the impulses.

10. In a printing telegraph system, the combination of a main line, a transmitting current distributor, a plurality of current control means arranged to cooperate with said distributor to form groups of current impulses for the line, a main line relay connected in series with the line and responsive to all line current impulses, a receiving cur-

rent distributor controlled by said main line relay, and selecting mechanism associated with the said receiving distributor to distribute the effects of the line impulses to operate a recording mechanism.

11. In a printing telegraph system, the combination of a main line, a main-line relay, a transmitting current distributor, a plurality of current control means arranged to cooperate with said distributor to form groups of impulses for the line, switching means for connecting one of the control means to and disconnecting the other from the distributor, another current distributor controlled by said main-line relay, and home recording means associated with the last-mentioned distributor and actuated in response to impulses transmitted by the first-mentioned distributor.
12. In a telegraph system, a line conductor and a source of current in series therewith, a set of selectable contacts arranged to close or to open said line circuit depending upon their selected or non-selected condition, means for selectively operating said contacts, a distributor mechanism for successively bringing said contacts into series relation with the line, a relay in circuit with said line responsive to the opening and closing thereof, a local circuit including a second distributor under the control of said relay, and means responding to an initial opening of said line circuit for initiating the operation of said second distributor.
13. In a telegraph system, a line conductor and a source of current in series therewith, a set of selectable contacts arranged to close or to open said line circuit depending upon their selected or non-selected condition, means for selectively operating said contacts, a distributor mechanism for successively bringing said contacts into series relation with the line, a relay in circuit with

said line responsive to each opening and closing thereof, a local circuit including a second distributor under the control of said relay, and means responding to an initial operation of said relay for initiating the operation of said second distributor.

14. In a printing telegraph system, a line circuit, a source of current normally in series therewith, a set of selectable relays, contacts therefor, means for selectively operating said relays to connect said contacts to said source of current, a distributor mechanism connected to said contacts, and means controlled by said relays for initially opening the line circuit and for effecting the release of the distributor mechanism to connect said selected contacts to the line.

15. In a printing telegraph system, a line circuit, a source of current normally connected therein, a current impulse distributor normally tending to rotate, a set of selectable contacts connected thereto, relays for selectively closing said contacts, and means controlled by the operation of said contacts for releasing the said distributor to close and to open the line circuit sequentially as determined by the position of said selectable contacts.

16. In a printing telegraph system, a line circuit, a source of current normally included therein, a distributor mechanism comprising conducting segments, a plurality of local circuits connected to said segments, circuit-closing mechanism for selectively connecting current to said local circuits, and means controlled by said circuit-closing mechanism for initially opening the line circuit and for initiating the operation of said distributor mechanism.

In witness whereof, we hereunto subscribe our names this 20th day of June A. D., 1917.

PAUL M. RAINES.
ANDREW D. DOWD.
